UNITED STATES PATENT OFFICE.

ALBERT L. LAMBERT, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA.

TORQUE DEVICE.

Application filed November 27, 1925. Serial No. 71,513.

This invention relates to a torque device, and more particularly relates to a torque device which may be incorporated in an automobile door or similar structure, where-
5 by the shape of the structure may be conformed to fit properly and accurately in the doorway or other opening in which the structure is intended to fit.

In building automobile bodies it is quite usual to build the door complete as a separate unit and then to mount the door on the completed body. It very often happens, especially when the door and the body are of metal, that due to the stamping operations 10 employed in shaping the metal members, and to the resiliency of the metal, and to unavoidable manufacturing variations, and possibly from other causes, the shapes and alignments of the door and the members 15 forming the doorway are not as intended, and it is found that when the door is applied to the body it does not properly fit into its doorway. In such structures a misfit of 20 this character is extremely objectionable and has been extremely difficult, if not im-
possible, to remedy heretofore.

The principal object of my invention is to provide means whereby a preformed door or similar structure may be adjusted into 25 such shape and alignment that it will fit its doorway properly and accurately, and to provide means for holding the door or similar structure in such adjusted shape or alignment. Another object of my invention is 30 to provide a door or similar structure which, after being constructed complete, is adjustable in shape and alignment, and may be conformed without reconstruction to fit 35 properly and accurately the doorway in 40 which it is intended to fit. A further object of this invention is to provide simple and readily operable means for effecting the above mentioned adjustment of the shape or alignment in a manufactured door or similar 45 structure. Other objects of this invention will be in part obvious and in part pointed out hereinafter.

In accordance with my invention, I attach 50 each end of a tube to opposite frame members of a door, or similar structure, and associate a torque device with this tube in such a way that when the torque device is tensioned it tends to rotate one end of the

tube, and the frame members attached thereto, relative to the other end of the tube and the frame member attached thereto, preferably at right angles to the axis of the tube. I provide accessible means for tensioning the torque device to establish sufficient torsional strains to place the door frame members into the desired alignment with respect to each other. I so arrange said adjusting means that the torque device and frame members will be maintained in the adjusted positions until further adjustment is made. 55 Accordingly, it will be apparent that the door before or after being completed and mounted in place may be adjusted in shape and in alignment to fit properly and accurately in its doorway. Even when the frame 60 members of the doorway are out of alignment with each other the door may be adjusted to fit the doorway of the shape presented, thus in any case avoiding the necessity of bringing the doorway frame members 65 into a certain alignment during manufac- 70 ture.

In order that a clearer understanding of my invention may be had, attention is hereby directed to the accompanying drawings forming a part of this application and illustrating one possible embodiment of my invention. Referring to the drawings, Fig. 1 is a front view of a door structure having 75 my invention embodied therein, a fragment 80 of the outer portion of the door being broken away; Fig. 2 is a vertical sectional view of the torque device and associated parts at the center of the door, the view being taken on the line 2-2 of Fig. 3; Fig. 3 is an end view 85 of the torque device and an attachment plate, and is taken on the lines 3-3 of Figs. 1 and 2; Figs. 4, 5 and 6 are cross sectional 90 views through different portions of the torque device and are taken respectively on the lines 4-4, 5-5, and 6-6 of Fig. 2; Fig. 7 is a sectional view of one of the 95 elements of the torque device; and Fig. 8 is an enlarged sectional view of a fragment 100 of another element of the torque device, showing the shape of the teeth on the surface of this element. Similar reference characters refer to similar parts throughout the several views of the drawings.

Referring to the drawings, to illustrate 105 the invention there is shown a structure in

the form of a door, comprising side frame members 1 and 2 which extend the full height of the door and are joined together by a top panel strip 3 and a lower panel 4. At about the middle of the door a metal strip 5 is secured to the inside of frame member 1 and a similar strip 6 is secured to the inside of frame member 2. A stiffening and reenforcing tube 7 extends between plates 5 and 6 and its ends are firmly secured thereto as by welding. A sleeve 8 is firmly fixed, as by welding, within this tube, near one end thereof and in this sleeve is firmly secured, also by welding if desired, one end of a rod 9, of torsional material, preferably metal for strength. Toward its other end this rod 9 is cut off square on two sides, as at 10, and the remaining curved surfaces are threaded as at 11 to receive a nut 12. This nut has an end flange 13 which seats rotatably within a recess in a sleeve 14, the end of the sleeve being turned over the flange 13, as at 15, so that sleeve 14 moves with nut 12 back and forth along rod 9 as the nut is turned thereon. Sleeve 14 has a center perforation which is squared to correspond with the squared cross-section of rod 9 so that rod 9 and sleeve 14 must turn together. The outside of sleeve 14 is provided with helical threads 16 which constantly engage with similar threads 17 formed on the inner surface of tube 7. Thus one end of rod 9 is rigidly connected with one end of tube 7 and door frame 1 through sleeve 8 and plate 5, and the other end of rod 9 is connected with tube 7 and the door frame 2 only through movable sleeve 14. Now, sleeve 14 cannot turn on rod but can be moved therealong by the turning of nut 12. On any such movement of sleeve 14 the engagement between threads 16 and 17 on sleeve 14 and tube 7 tends to cause the engaged portions of these members to rotate in opposite directions transversely of the axis of rod 9. At their other ends tube 7 and rod 9 are anchored together by sleeve 8 and here the oppositely directed torsional strains cannot move rod 9 and tube 7 relative to each other, with the result that whenever nut 12 is adjusted the relatively movable ends of tube 7 and rod 9 are rotated in opposite directions and frame member 2 is rotated with respect to frame member 1. Obviously the relative amount of rotation of the free end of rod 9 and frame member 2 will depend upon the relative torsional resistances of the parts. The amount of combined rotation for a given amount of advance of sleeve 14 on rod 9 (or per turn of nut 12) will depend upon the pitch of threads 16 and 17.

From the above it will be apparent that a structure having the above invention and device embodied therein may readily and easily be adjusted in shape and in alignment

of its parts, and such adjustment may be made either before or after the structure has been completed, and even after the structure, such as a door, has been paneled and mounted in place at its doorway. If the door upon completion is found to be out of the desired alignment it may be brought into alignment. If the doorway is out of proper alignment, the door may be brought into the same alignment so as to fit properly and accurately into the distorted doorway. The structure will retain any adjustment into which it has been placed by the adjustment of nut 12 on rod 9.

In the embodiment shown, if nut 12 is turned clockwise on rod 9, referring to Fig. 3, to advance sleeve 14 thereon, the free end of rod 9 will be turned clockwise and the engaged end of tube 7 and frame member 2 will be rotated counterclockwise, while frame member 1 will be stationary. On reverse movement of nut 12 the said rotational movements will be reversed, member 1 remaining stationary.

The nut 12 is accessible by means of a socket wrench, or other tool, through a hole 18 passing through frame member 2 and re-enforcing plate 6.

The tube 7 not only cooperates with the torque device to permit adjustment of the door but also serves as a very effective reenforcement thereto, and effectively resists undesired distortion of the door by the usual torsional strains to which a door is subjected in normal usage. The plates 5 and 6 not only serve as convenient means for attaching the tube 7 firmly and rigidly to the door frame members but also stiffen and reinforce the structure. It will be noticed that the structure may be built exceedingly light in weight and of few parts while at the same time is extremely sturdy and rigid as well as being adjustable in shape or alignment at will by a convenient and simple operation.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:—

1. A torque device of the character described, including, in combination, two torsionable members in parallel alignment with each other, said members being rigidly connected at one point, and means, connecting said members, whereby at another point one of said members may be rotated with respect to the other member.

2. A torque device of the character described, including, in combination, two tor-

5 sionable rods in parallel alignment with each other, said members being rigidly connected at one point, and means, connecting said members, whereby at another point one of said members may be rotated with respect to the other member, and automatically held in rotated position.

10 3. A torque device of the character described, including, in combination, two torsionable members one disposed within the other, said members being rigidly connected at one point, and means, connecting said members, whereby at another point said members may be rotated in opposite directions.

15 4. A torque device of the character described, including, in combination, two torsionable members in parallel alignment one disposed within the other, said members being rigidly connected at one point, means, connecting said members, whereby at another point said members may be rotated in opposite directions, and means for locking said members in the rotated positions.

20 5. A torque device of the character described, including, in combination, two torsionable members in parallel alignment with each other, said members being non-rotationally connected at one point, and means, connecting said members, whereby at another point said members may be rotated in opposite directions, said means including a coupling movable axially with respect to both said members and so engaging said members that when said coupling is moved axially said members are twisted thereby axially in opposite directions.

25 6. A torque device of the character described, including, in combination, two torsionable members in parallel alignment with each other, said members being non-rotationally connected at one point, and means, connecting said members, whereby at another point said members may be rotated in opposite directions, said means including a coupling movable axially with respect to both said members and so engaging said members that when said coupling is moved axially said members are twisted thereby axially in opposite directions, said coupling having a threaded engagement with one of said members.

30 7. A torque device of the character described, including, in combination, two torsionable members in parallel alignment with each other, said members being non-rotationally connected at one point, and means, connecting said members, whereby at another point said members may be rotated in opposite directions, said means including a coupling movable axially with respect to both said members and so engaging said members that when said coupling is moved axially said members are twisted thereby axially in opposite directions, said coupling

35 having a threaded engagement with one of said members, and being non-rotatable with respect to the other member.

8. In a torque device of the character described, in combination, a tube, a rod within said tube and rigidly connected thereto at one point, and means connecting said rod and tube at another point whereby said rod and tube may be twisted simultaneously in opposite directions. 75

9. In a torque device of the character described, in combination, a tube, a rod within said tube and rigidly connected thereto at one point, and means connecting said rod and tube at another point whereby said rod and tube may be twisted simultaneously in opposite directions, said means including a coupling movable axially with respect to said rod and tube, engaging said rod for rotation therewith and in threaded engagement with said tube for relative rotational movement with respect thereto. 80 85

10. In a torque device of the character described, in combination, a tube, a rod within said tube and rigidly connected thereto at one point, means connecting said rod and tube at another point whereby said rod and tube may be twisted simultaneously in opposite directions, said means including a coupling movable axially with respect to said rod and tube, engaging said rod for rotation therewith and in threaded engagement with said tube for relative rotational movement with respect thereto, and means for adjusting said coupling axially of said tube and rod. 90 95 100

11. In a torque device of the character described, in combination, a tube, a rod within said tube and rigidly connected thereto at one point, and means connecting said rod and tube at another point whereby said rod and tube may be twisted simultaneously in opposite directions, said means including a coupling movable axially with respect to said rod and tube, engaging said rod for rotation therewith and in threaded engagement with said tube for relative rotational movement with respect thereto, said rod having a threaded portion, and a nut on said threaded portion engaging said coupling, whereby said coupling may be adjusted and held in adjusted position axially of the tube and rod. 110 115

12. In a torque device of the character described, in combination, a tube, a rod within said tube and rigidly connected thereto at one point, and means connecting said rod and tube at another point whereby said rod and tube may be twisted simultaneously in opposite directions, said means including a coupling movable axially with respect to said rod and tube, engaging said rod for rotation therewith and in threaded engagement with said tube for relative rotational movement with respect thereto, said rod hav- 120 125 130

ing a threaded portion, and a nut on said threaded portion engaging said coupling whereby said coupling may be adjusted and held in adjusted position axially of the tube and rod, said rod having a squared portion and rod, said rod having a squared portion and said coupling having a perforation of complementary shape through which said rod extends.

13. In a torque device of the character described, in combination, a tube, a rod within said tube and rigidly connected thereto at one point, and means connecting said rod and tube at another point whereby said rod and tube may be twisted simultaneously in opposite directions, said means including a coupling movable axially with respect to said rod and tube, engaging said rod for rotation therewith and in threaded engagement with said tube for relative rotational movement with respect thereto, said rod having a threaded portion, and a nut on said threaded portion engaging said coupling,

whereby said coupling may be adjusted and held in adjusted position axially of the tube and rod, said rod having a squared portion and said coupling having a perforation of complementary shape through which said rod extends, said tube having an interior threaded portion, and said coupling having threads engaging said tube threads. 30

14. The combination with a pair of opposed frame members having a reinforcing tube extending therebetween and rigidly connected thereto at its ends, of a torque rod within said tube and rigidly secured to said tube adjacent one end thereof, and means connecting said rod and tube at the other end for simultaneously twisting said tube and rod in opposite directions, whereby the alignment of said frame members may be 40 varied.

This specification signed this 23 day of November, 1925.

ALBERT L. LAMBERT.
